UNITED STATES PATENT OFFICE.

DERWIN E. BUTLER, OF CHESTERFIELD, FULTON COUNTY, OHIO; AURELIA O. BUTLER EXECUTRIX OF SAID DERWIN E. BUTLER, DECEASED.

FEED-WATER REGULATOR.

SPECIFICATION forming part of Letters Patent No. 356,400, dated January 18, 1887.

Application filed June 24, 1886. Serial No. 206,129. (No model.)

To all whom it may concern:

Be it known that I, DERWIN E. BUTLER, of Chesterfield, (Oak Shade P. O.), in the county of Fulton and the State of Ohio, have invented 5 a new and Improved Feed-Water Regulator, of which the following is a full, clear, and exact description.

The object of my invention is to provide a new and improved feed-water regulator, which 10 is simple in construction and automatic in operation.

The invention consists of various parts and details and combinations of the same, as will be fully described hereinafter, and then pointed 15 out in the claims.

Reference is to be had to the accompanying drawings, forming a part of this specification, in which similar letters of reference indicate corresponding parts in all the figures.

20 Figure 1 is a sectional elevation of my improvement. Fig. 2 is an inverted sectional plan view of the same on the line *x x* of Fig. 1. Fig. 3 is a vertical cross-section of the same on the line *y y* of Fig. 1. Fig. 4 is a sectional end view on the line *z z* of Fig. 2. Fig. 25 5 is a sectional plan view of the tank-valve on the line *w w* of Fig. 3. Fig. 6 is a similar view of the same on the line *u u* of Fig. 3.

The tank A, of suitable size and construction, 30 is provided on the inside with the bent tube B, secured to the bottom of the tank and extending to the outside of the same. The part B' of the pipe B connects with the water-supply, and the other part, B'', is provided 35 with a partition, B³. The part below the partition B³ is provided with a pipe, C, leading to the boiler D, placed below the tank A. The pipe C is provided on the outside of the boiler D with a valve, C', and to the lower end of the 40 pipe C is pivoted a skimmer, C''.

On the part B'' of the pipe B turns a valve, E, provided in its top with the ports E', which connect with corresponding ports, B⁴, in the part B'', above the partition B³, and the valve 45 E is also provided with ports E'', which correspond with the ports B³ in the part B'' below the partition B³. When the interior of the pipe B is connected with the inside of the tank by means of the ports E' and E'', the ports E'' 50 and B³ are disconnected, and vice versa.

A link, F, connects the valve E with the piston G, operating in the cylinder H, which opens into the tank A. The piston G is provided with the piston-rod I, which extends to the outside of the cylinder and is connected 55 with the coil-spring J. On the piston-rod I is pivoted an arm, K, having the notches K' and K'', which engage alternately with the shaft M, passing transversely through the cylinder H, and having the lug L on the inside, 60 and the outside of the shaft M is provided with a crank-arm, N, which is connected by the link O with the crank-arm P, secured to the shaft Q, passing into the tank A, and carrying on the inside of said tank an arm, R, 65 provided on its end with a float, S.

A rod T, having its bearing on the piston-rod I, and moving with the same, is provided with a pin, T', operating on the arm K, and with a handle, T'', by which the rod T can be 70 turned. The spring U, secured to the top of the piston-rod I, acts on the arm K.

The operation is as follows: As shown in Fig. 1, the boiler D is filled to the high-water mark with water, and the tank A is partly filled 75 with water. The valve E is in such a position that it connects the interior of the tank A with the pipe C and the boiler while the water-supply is shut off. As soon as the water in the boiler diminishes so that the water-level 80 is below the lower end of the pipe C, which permits the steam in the boiler to pass up through the pipe C into the tank A by means of the ports B³ and E'', the said steam exerts its pressure on the water in the tank A, and 85 causes the water to flow down into the boiler by the ports through which the steam passed up into the tank. As soon as the water in the boiler covers the lower end of the pipe C the flow of the water from the tank A ceases. 90 When the operator finds that the tank A is empty, he turns the rod T, by means of the handle T'', so that the pin T' raises the arm K, which is thus disengaged from the shaft M by its notch K''. As soon as the level of the water 95 in the boiler is below the lower end of the pipe C the steam passes into the tank A and the pressure of the steam forces the piston G to move outward, and when in its extreme outward position the operator turns the handle 100

T² back to its former position, which causes the arm K to swing downward, and the notch K' falls over the shaft M, which locks the piston-rod I and the piston G in its outer position. This outward motion of the piston G turns the valve E so that the ports B³ and E² are closed and the ports B⁴ and E' are placed in communication with each other, which connects the supply of water with the interior of the tank A. As the steam remaining in the tank A condenses it forms a vacuum in the same, which causes suction in the supply-pipe D', and the water enters the tank A through the ports B⁴ and E'. As the water rises in the tank A it raises the float S, and when the same reaches its uppermost position the lug L on the shaft M, which is turned by the rising of the float S, causes the arm K to swing upward, and thereby disengages the shaft M from the notch K'. The spring J, which was compressed by the outward motion of the piston G, now exerts its pressure and forces the piston G, the piston-rod I, and the rod T inward to their former position, (shown in Fig. 1,) where-by the valve E is turned so as to shut off the water-supply by closing the ports B⁴ and E', and establishes communication with the boiler by opening the ports B⁵ and E². The above-described operation of feeding the boiler from the tank A again takes place. The spring U holds the arm K in a locked position. The connection between the tank A and the boiler may also be shut off by the valve C', if desired.

Having thus fully described my invention, I claim as new and desire to secure by Letters Patent—

1. In a feed-water regulator, the combina-

tion of the boiler D and the tank A with the pipes B and C, the valve E, operating on the pipe B, the piston G, operating the valve E, and the float S, unlocking the piston G, substantially as shown and described.

2. In a feed-water regulator, the combination of the boiler D and the tank A with the pipes B and C, the valve E, operating on the pipe B, the piston G, operating the valve E, the piston-rod I, the spring J, and the float S, unlocking the piston G, substantially as shown and described.

3. In a feed-water regulator, the combination of the boiler D and the tank A with the pipes B and C, the valve E, alternately connecting the water-supply and the boiler with the tank A, the piston G, connected by the link F with the valve E, the piston-rod I, and the spring J, substantially as shown and described.

4. In a feed-water regulator, the combination of the tank A with the pipe B, provided with the parts B' and B², of which the part B² is provided with the partition B³ and the ports B⁴ and B⁵, and the valve E, having the ports E' and E², substantially as shown and described.

5. In a feed-water regulator, the piston G, the rod I, the spring J, and the arm K, pivoted to the said piston-rod I, and having the notches K' and K², in combination with the float S, attached to the shaft Q and operating the shaft M, having the lug L, substantially as shown and described.

DERWIN E. BUTLER.
